CHARLES D. MARSHALL, OF PITTSBURGH, PENNSYLVANIA, ASSIGNOR TO MCCLINTIC-MARSHALL CORPORATION, OF BETHLEHEM, PENNSYLVANIA, A CORPORATION OF PENNSYLVANIA

MECHANISM FOR RIVETING COLUMNS, BEAMS, ETC.

Application filed November 30, 1926. Serial No. 151,658.

This invention relates to new and improved mechanism for riveting columns, beams, and other metallic structural shapes and members. Riveting of beams and other structural shapes, as heretofore practiced, has been a slow, troublesome, and costly operation, requiring the services of quite a number of operators for handling the work and manipulating the apparatus.

Among the objects of the present invention are, to provide a new and improved mechanism for riveting members of the character specified, including a riveter adjustably mounted to enable it to be readily moved into the desired operative positions; to provide simple and efficient means for positioning and holding the work relatively to the riveter; and to provide means for effecting an adjustment of the operating parts and the manipulation thereof by operable means arranged and assembled for effecting successive steps in the riveting operation.

A still further object of the present invention is to provide a riveting mechanism that is capable of driving the rivets either cold or heated, and at a considerable saving over the old methods, and a mechanism of such a character that the number of operators required for operating the mechanism and handling the work is greatly reduced.

In the accompanying drawings, which illustrate an application of my invention:

Fig. 1 is a diagrammatic plan view of a riveting mechanism constructed in accordance with my invention;

Fig. 2, a side elevational view;

Fig. 3, a detailed side elevational view, particularly showing the riveter, the manner of mounting the riveter on a turn-table, and the fluid actuated mechanism for operating various parts of the apparatus;

Fig. 4, a detail view particularly showing the means for raising and lowering the riveter relatively to the work;

Fig. 5, a part plan and a part sectional view, the section being taken on line V—V of Fig. 7;

Fig. 6, a detail vertical sectional view, the section being taken on line VI—VI of Fig. 5;

Fig. 7, a detail vertical sectional view, the

section being taken on line VII—VII of Fig. 5;

Fig. 8, an enlarged detail view, particularly showing means for shifting the movable frame, on which the riveter is carried, on its supporting table;

Fig. 9, a part end elevational view and a part sectional view, showing the gripper or means for passing the work to and from the riveter, the section being taken on line IX—IX of Fig. 1;

Fig. 10, a part plan view and a part sectional view, showing the said gripper mechanism.

As illustrated and as preferred, the improved riveting mechanism constructed in accordance with my invention includes a riveter 5, designed to be used in connection with hydraulic-pneumatic means for actuating the movable parts of the riveter and for moving the riveter into operative positions relative to the work. 6 designates supporting means positioned in advance of the riveter 5, and 7, corresponding means located at the opposite side of the riveter. Both of the said supporting means 6 and 7 are shown in the form of laterally adjustable wheels, but other supporting means or tables may be employed.

The riveter 5 is carried on a turn-table or rotatable platform 8, said platform 8 being in turn mounted on anti-friction bearings 9, disposed on a plate structure 10 carried on a suitable foundation 11. By mounting the riveter on the turn-table or equivalent means, the riveter may be rotated, so that it may operate upon, for example, the opposite side of a beam as it is passed through the riveter from an opposite direction.

In riveting mechanisms of the character specified, it is of the utmost importance that means be provided for enabling the riveter to be readily adjusted for riveting members varying in size and form, and, in the construction shown, I have provided means for accomplishing the said adjustments.

As illustrated, the riveter includes a yoke-shaped body and is pivotally mounted on a movable frame 12. This frame is supported on wheels 13 positioned on a track on the

turn-table 8. Extending downwardly from the riveter are two depending plate members or arms 14, said members being bolted to two side faces of the yoke-shaped body 5 of the riveter. Each arm is journaled to a vertically movable trunnion 16, the latter being mounted for vertical adjustment in the movable frame 12 on guides 16a.

The riveter 5 is preferably mounted on its 10 trunnions 16, through the arms 14, in such a manner as to be slightly tilted away from the work A, while in inoperative position. Mounting the riveter in this way necessitates 15 tilting it slightly forward towards the work prior to performing the riveting operation. Any suitable means may be utilized for tilting the riveter on its pivot points. As shown, I have provided fluid operated means including a cylinder 17, a piston 18, a piston rod 20 19, and a flexible connection 20 joining the piston rod and the body portion of the riveter. The piston is designed to be operated by means of a fluid conveyed to the cylinder 17 through suitable connections hereinafter described. The respective jaws of the riveter 5 are designed to carry an anvil or die 21, and an upsetting tool or hammer 22.

In addition to the tool 22, one jaw carries the tool actuating means including a cylinder 30 23 and its fluid actuated plunger 24 operatively seated therein. Plunger 24 of this mechanism is moved either up or down by fluid pressure conveyed thereto in a manner to be hereinafter described.

The riveter supporting frame 12 is adapted 35 to be moved radially of the turn-table 8, and the riveter being carried thereby will be moved laterally of the work A, or transversely of the mechanism. This lateral movement 40 relative to the work permits the riveter to be shifted for the purpose of taking care of staggered rows of rivets and for other purposes. The actuating means for effecting this lateral movement are particularly shown 45 in the sectional detail view, Fig. 7, and, as there illustrated, include a fluid cylinder 26 having means hereinafter described for admitting fluid to opposite sides of a piston head 27 disposed in the cylinder 26.

Cylinder 26 is bolted or otherwise secured 50 to the turn-table and is disposed in a recess of the movable frame 12; its piston 27 has a piston rod 28 extending from opposite sides thereof to cross bars 12a of frame 12, the cross bars spanning the recess of the frame at points beyond the ends of the cylinder, and spaced from said cylinder to permit movement of the frame in either direction of movement of the piston. Air enters the cylinder 26 through a slide valve 29, the air inlet to the valve being indicated by numeral 29a; and 30 designates an exhaust opening from the valve 29, see Fig. 8. The valve 29 is controlled by levers 31 disposed at opposite sides of the riveter, and the levers in turn

are connected by suitable link connections, as clearly shown in Figs. 2 and 3, to a valve rod 32. Movement of the piston 27 in either direction causes the frame to be moved laterally of the work. The shifting of the frame laterally by means of the air cylinder and the mechanism described provides for quickly moving the heavy apparatus to the position desired, with a minimum of expenditure of power and labor.

In order to stop the riveter at the desired position, I provide means including hand-operated screw bars 33 and 34, screw threaded to one of the members 12a at one end of the framing 12, said screw bars being journaled at one end in lugs on the cylinder casting. Bar 33 has a shoulder 34a adapted to push against a lug 35, and bar 34 has a head 35 adapted to pull against a lug 37.

In addition to the lateral shifting, as just described, means are also provided for raising and lowering the riveter in a vertical plane. The means for effecting this vertical movement include screw bars 38 journaled in the upper portion of the framing 12 on opposite sides thereof having their lower ends threaded into the trunnion members 16. The upper end of each screw bar has secured thereto a pinion 39, and said pinions are arranged to mesh with a drive gear 40 on a shaft 40a, see Fig. 7.

The shaft 40a is driven by a worm 41 and a worm wheel 42, respectively, actuated by a hand crank 43.

From the foregoing, it will be noted that means have been provided for adjusting the riveter relatively to the work A by tilting it, by raising and lowering it, and by moving the riveter laterally towards and away from the work. It will be further noted that the riveter, being mounted on the turn-table, may be revolved 180 degrees, as above stated, thereby bringing the riveter into operative position on the opposite side of the beam or other structural member being riveted.

Located adjacent to the work supporting means 7 is a mechanism designed to grasp and pass the work between the jaws of the riveter for effecting the riveting operation. As shown, this construction comprises a gripper, designated generally by the numeral 50, said gripper or tong-like structure including a fixed jaw 51 and a movable jaw 52. The fixed jaw is secured to a carriage 53, the latter being designed to be moved by a sprocket and chain drive. In this driving means, I employ a chain 54 designed to cooperate with a sprocket wheel 55 mounted on a shaft 56 and to be passed over an idler wheel 57. Said shaft or spindle 56 is adapted to be operated by hand-wheels 58 located at opposite sides of the machine. The carriage 53 is mounted on wheels 59 adapted to travel on a suitable track 60 carried on standards 61.

This work gripper and its operating mech-

anism are particularly shown by Figs. 9 and 10 of the drawings, and by referring to these views, it will be noted that I have provided guide rollers 62 and 63 respectively, designed to prevent lateral shifting of the carriage 53 or an upward or tilting movement thereof during the travel of said carriage and during the pulling strains to which the carriage is subjected. The movable jaw 52 is pivotally connected to the fixed jaw at 64 and has its inner end 65 connected with an adjusting screw 66.

For the purpose of supporting the work in the desired position while on or passing over the revolving table 8, I provide supporting wheels 67 and 68. These wheels are carried on shafts 69 supported by standards 70 mounted on the turn-table. Like the corresponding supporting means 6 and 7, they may be adjusted towards and away from the longitudinal center of the machine.

In operation, the work, indicated by the letter A, is placed in position on the table 6 and then moved up into position to be caught by the gripper mechanism. After being engaged by this mechanism, an operator rotates operating wheels 58 to move the work longitudinally of the apparatus, until an undriven rivet is laterally opposite the center line of the dies 21 and 22. At this time, the riveter 5 is at its outer end of lateral travel on the turn-table, and is also tilted back slightly away from the work.

The riveter is next moved inwardly toward the work by manipulating lever 31. A movement of lever 31 will move a slide 29b in valve structure 29 (see Fig. 6), thereby connecting one of the ports 79, Fig. 7, with the atmosphere through port 30. The act of priming either one of the two ports 79 with the port 30 opens communication between the other port 79 and the main air supply pipe or header 80 through a pipe 81. Valve structure 29 is designed to operate so that one end of cylinder 26 will, through port 30, be in communication with the atmosphere and its other end in open communication with the fluid from pipe connection 81, thus causing the piston to travel in its cylinder to actuate the movable frame 12 and bring the riveter into such position that it may be tilted by moving operating lever 83. Moving lever 83 allows fluid to pass to cylinder 17 from the supply pipe or header 80 by way of valve 84 and pipes 85 and 86, thereby moving piston 18 upwardly and through its operating connections tilting the riveter with its die 21 into contact with an undriven rivet.

An operator next manipulates lever 87, see Fig. 3, which produces a movement of slides in valves 88 and 89. These valves are connected to the header 80 through line 89a. Movement of the slide in valve 88 connects to the atmosphere through line 91 the upper portion of cylinder 23, an air chamber in a

valve structure 92, and an air chamber in a valve structure 93. Simultaneously with the movement of the slide in valve 88, a slide in valve 89 is moved, connecting to the atmosphere through line 94 and air chamber in double valve 95.

It will be understood, of course, that, prior to the exhaustion just described, compressed air has been admitted through line 91 to cylinder 23 and the valves 92, 93 and 95.

The exhausting of the compressed air in valve 92 closed ports in that valve, which ports connected a cylinder 96 to the atmosphere. The exhausting of the compressed air at valve 93 opened ports in that valve, permitting air to flow directly from header 80 into valve 93, through pipe 97 into cylinder 98.

The entry of compressed air into cylinder 98 moves a piston upward and drives oil out of the upper end of cylinder 98 through valve 99, and thence through a pipe 100 into cylinder 23. This flow of oil produces an upward movement of plunger 24, causing it to rise until stopped by the engagement of die 22 against the rivet. Oil will continue to tend to flow to cylinder 23 until its pressure becomes that of the compressed air in header 80, at which time, a plunger in valve 99 moves so as to shut-off that passage in valve 99 which connects line 100 with cylinder 98. Movement of the plunger in valve 99 actuates valve 95 so as to allow air to enter cylinder 96. Compressed air entering cylinder 96 causes an upward movement of a piston 101 therein, and this movement of piston 101 through cylinder 96 displaces oil from a cylinder 102, through line 103, through valve 99, through line 100, to cylinder 23, causing the upsetting of the rivet in the work.

Cylinder 102 is connected to regulating valve 104 through pipe 105, and when the oil pressure in cylinder 102 is sufficient to overcome the resistance of a spring loaded plunger 106 in valve 104, the plunger moves upward, actuating the slide in valve 89, thereby causing compressed air to flow from that valve to valve 95, closing valve 95, and thereby preventing any more flow of compressed air into cylinder 96. This immediately stops movement of plunger 24, and it will continue to stay pressed against the rivet until the operator reverses lever 87, thus reversing the slide in valve 88, which will permit compressed air to flow to valve 92, opening it and exhausting the compressed air from under piston head 101.

The compressed air will, at the same time, enter the upper part of cylinder 23, through line 91, producing a force upon plunger 24, thus moving plunger 24 downwardly and driving the oil out of cylinder 23 back to cylinders 102 and 98.

With the movement of the slide in valve 88, compressed air also flows through line 91 to

valve 93, closing that valve to the flow of compressed air from header 80 and opening ports in the valve, permitting the compressed air in cylinder 98 to exhaust back through pipe 97 and valve 98 to the atmosphere.

The exhausting of cylinder 96 is accomplished by a decrease of oil pressure in cylinder 102, line 103, and valve 99, and line 100, which permits the aforementioned plunger in valve 99 to drop back to such position as to cause communication of line 100 with cylinder 98 through valve 99, thus permitting the return of oil from cylinder 23 to cylinder 98. This completes automatically the proper driving of the rivet, and the operator next reverses his formerly described manipulations of levers 83 and 31 in order to tilt the riveter off the rivet and move the riveter away from the work in order that the work may be moved so as to bring the next rivet in position for being driven.

The work is now moved through the machine until all rivets accessible from that position of the riveter are driven. The work is then moved still further along the tracks 60, until the work is clear of the turn-table. The turn-table is next revolved, moving the riveter to the opposite side of the work, after which the work is passed back through the riveter and rivets driven, as previously described.

What I claim is:

1. In mechanism for riveting structural metallic members as beams, columns, and the like, a turntable movable on a vertical axis, a frame adjustably mounted on the turntable, an upstanding riveter pivotally mounted adjacent its lower end on the frame having a work-receiving opening in one side thereof, rivet-upsetting means carried by the riveter adjacent said opening, means for tilting the riveter, and means for supporting a structural member located adjacent the riveter and including an element mounted on the turn-table.

2. In mechanism for riveting structural metallic members as beams, columns, and the like, a horizontal rotatable support, an upstanding riveter mounted adjacent its lower end on the support and having a work-receiving opening in one side thereof, rivet-upsetting means carried by the riveter adjacent said opening, work supporting means on the support adjacent the riveter, power means for transversely moving the riveter on the rotatable support, and means for moving the riveter in a vertical plane relative to the support.

3. In combination, a plurality of work supports, a turntable, a riveting machine, said riveting machine and one of the supports being carried by said turntable, whereby the machine may be positioned on opposite sides of work, the work support on the turntable being positioned for alinement with the remainder of the work supports in both posi-

tions of the turntable and riveting machine.

4. In combination, a plurality of work supports, a turntable, a riveting machine movable relatively to the turntable, means normally maintaining the riveting machine immovable relative to the turntable under fluid pressure, said riveting machine and one of the supports being carried by the turntable, whereby the machine may be positioned on opposite sides of work, the work support on the turntable being positioned for alinement with the remainder of the work supports in both positions of the turntable and riveting machine.

5. In mechanism for riveting structural metallic members such as beams, columns and the like, a turntable movable on a vertical axis, an upstanding riveter mounted on the turntable having a work-receiving opening in one side thereof, rivet-upsetting means on the riveter adjacent said opening, means for adjustably moving the riveter on the table, and means for supporting a structural member carried by the table.

6. In combination, a plurality of work supports, a turntable, a riveting machine, said riveting machine and a pair of supports being carried by said turntable, the supports of said pair being located on opposite sides of and equidistantly spaced from the riveter, whereby the machine may be positioned on opposite sides of work, the work supports on the turntable being positioned for alinement with the remainder of the work supports in both positions of the turntable and riveting machine.

7. In combination, a plurality of work supports, a turntable, a riveting machine, said riveting machine and one of the supports being carried by said turntable, whereby the machine may be positioned on opposite sides of the work, the work support on the turntable being positioned for alinement with the remainder of the work supports in both positions of the turntable and riveting machine, means mounting the riveting machine for tilting movement on a horizontal axis, and the riveting machine having a work-receiving opening above said axis.

8. In combination, a plurality of work supports, a turntable, a riveting machine, said riveting machine and one of the supports being carried by said turntable whereby the machine may be positioned on opposite sides of work, the work support on the turntable being positioned for alinement with the remainder of the work supports in both positions of the turntable and riveting machine, a frame movable laterally on said turntable, means pivoting the riveting machine on a horizontal axis to said frame, mechanism to adjust the last mentioned means and riveting machine in a vertical plane, said riveting machine having a work receiving opening and rivet upsetting

means above the axis thereof and adjacent one side thereof.

ing operable to tilt the yoke and to automatically vary in relative position to compensate for adjustment of the said trunnion members.

In testimony whereof I affix my signature.

CHARLES D. MARSHALL.

9. In combination, a plurality of work supports, a turntable, a yoke substantially vertically disposed, said yoke and one of the supports being carried by said turntable, whereby the yoke may be positioned on opposite sides of work, the work support on the turntable being positioned for alinement with the remainder of the work supports in both positions of the turntable and riveting machine, a frame movable laterally on said turntable, means pivoting said yoke adjacent the lower end thereof to said frame for tilting movement on a horizontal axis, an upsetting means carried by the yoke, and fluid pressure means operable from a common source to operate the upsetting means and to cause tilting movement of the yoke.

10. In combination, a plurality of work supports, a turntable, a riveting machine, said riveting machine and one of the supports being carried by said turntable whereby the machine may be positioned on opposite sides of work, the work support on the turntable being positioned for alinement with the remainder of the work supports in both positions of the turntable and riveting machine, two means constituting the sole support for the riveting machine, the first means comprising a pivotal connection, the second means comprising a piston and cylinder operable to tilt the riveting machine, one of the parts of the second means being pivoted to the riveting machine on an axis parallel to the said pivotal connection.

11. In combination, a plurality of work supports, a turntable, a riveting machine comprising a yoke, said yoke having a work receiving opening and rivet-upsetting means at one side thereof, said riveting machine being pivoted below said opening to said turntable and one of the supports being carried by said turntable whereby the machine may be positioned on opposite sides of work, the work support on the turntable being positioned for alinement with the remainder of the work supports in both positions of the turntable and riveting machine, means operable to move the yoke vertically, means operable to move the yoke laterally, and a coacting piston member and cylinder member operable to tilt the yoke, one of said members being pivoted to the yoke and the other member being carried by the turntable.

12. In a riveting machine, a supporting member, a yoke having depending arms, trunnion members to which the arms are pivoted on a horizontal axis, means located between the arms and operable to adjustably support the trunnion members, a cylinder carried by said supporting member, a piston operable in said cylinder and pivotally connected to the yoke on an axis parallel to the axis of said trunnion means, said piston and cylinder be-
